UNITED STATES PATENT OFFICE.

HENRY A. DITZELL, OF ROMULUS, NEW YORK.

COMBINED LETTER-SHEET AND ENVELOPE.

SPECIFICATION forming part of Letters Patent No. 398,822, dated March 5, 1889.

Application filed January 12, 1887. Serial No. 224,168. (No model.)

To all whom it may concern:

Be it known that I, HENRY A. DITZELL, of Romulus, in the county of Seneca and State of New York, have invented a new and useful Improvement in Combined Letter-Sheet and Envelope, of which the following is a specification.

My invention is in the nature of certain improvements in combined letter-sheets and envelopes; and it consists in the peculiar construction and arrangement of parts herein-after described, and pointed out in the claim.

Figure 1 is an inside face view of the combined letter-sheet and envelope. Fig. 2 is a similar view of a modification, and Fig. 3 is a view of the folded sheet from the address side.

Referring to Fig. 1, A is the sheet, which is adapted to be folded twice—first on the line *a* *a* and then on line *b* *b*. At the long side of one of the quarter-sections of the sheet is formed the folding flap B, which is gummed along its edge at *c*, and which gummed portion extends around the end of the quarter-section at *d*, outside the outline of the letter-sheet. At the opposite end of the letter-sheet is formed the projecting tag C, whose length equals half the width of the letter-sheet. This projecting tag is designed to receive the printed return address, and when the sheet is folded a portion of this projecting tag (the part *e* included between the dotted lines) lies against and adheres to the gummed edge *d*, while the outer portion of the tag, bearing the return address, projects beyond the gummed edge *d*, and is visible from the front or address side of the envelope, as seen in Fig. 3.

To fold the sheet seen in Fig. 1, the right-hand side of the sheet is first folded on the line *a* *a*, and then is folded on the line *b* *b*. This latter movement brings the space *e* of projection C into adhesive contact with gummed edge *d*, and the flap B is then folded over and its edge *c* made to adhere. It will thus be seen that the letter-sheet only re-

quires to be run through the press once in 45 printing both the letter-head and return-address words, and yet the peculiar construction and arrangement of the projecting tag C permit the return address to be visible on the front of the envelope. 50

I do not confine myself to the exact location of the projection C, since it may be made to overlap the gummed edge *d* by being located in other positions than that shown in Fig. 1. Thus in Fig. 2 it may be placed at 55 the same end of the sheet as the gummed edge *d*, so that when the lower edge of the letter-sheet is folded up to the lower edge of gummed surface *d*, and then the right-hand edges are folded over to the junction of the 60 flap and letter-sheet, the parts C, *e*, and *d* combine to give substantially the same result as in Figs. 1 and 3.

I am aware that it is not new to make a combined letter-sheet and envelope, and I 65 only claim the letter-sheet envelope having the projection C disposed so as to permit its inner side bearing the return address being made visible on the front of the envelope by coming in adhesive contact with and overlapping the adapted parts *d* and *e*. 70

Having thus described my invention, what I claim as new is—

The combined letter-sheet and envelope having the gummed flap B and edge *d* extending outside the outline of the body part of the sheet, and having a projecting tag, C, for the return address, adapted to overlap and extend beyond the edge *d* and expose on the front of the folded sheet or envelope a part 80 of the inner face of the sheet, as described. 75

In testimony whereof I affix my signature in presence of two witnesses.

HENRY A. DITZELL.
